WILLIAM H. KLOCKE, OF WOODHAVEN, NEW YORK, ASSIGNOR TO THE CLEVELAND GRAPHITE BRONZE COMPANY, OF CLEVELAND, OHIO, A CORPORATION OF OHIO

BEARING BODY AND METHOD OF MAKING SAME

Application filed September 6, 1927. Serial No. 217,658.

The principal object of this invention is to provide a tubular member adapted to receive a coating.

Another object is to provide a tubular member having its surface roughened to increase the strength of adhesion between said member and a coating to be applied thereto.

A further object is to provide a tubular member pressed from sheet steel and having its surfaces roughened to adapt it to receive and retain a coating.

A still further object is to devise a novel method of making steel tubes of uniform thickness and having roughened surfaces.

15 The most advantageous use which I have found for my invention is in the manufacture of bearings. Thereupon the roughened steel tube is used as a supporting body for a coating of Babbitt metal for forming the surface 20 of a bearing proper.

To the accomplishment of the foregoing and related ends, said invention, then consists of the means hereinafter fully described and particularly pointed out in the claims.

25 The annexed drawing and the following description set forth in detail certain mechanism embodying the invention, such disclosed means constituting, however, but one of various mechanical forms in which the principle of the invention may be used.

In said annexed drawings:

Fig. 1 is a plan of a piece of sheet metal such as is used in the practice of my invention to form the tubular member; Fig. 2 is 35 an edge elevation thereof; Fig. 3 is a view similar to Fig. 2, the first step in the process for forming the sheet into a tube having been taken; Fig. 4 is a view similar to Fig. 3, showing said piece after the second step in 40 said process; Fig. 5 is a view similar to Fig. 4 after the last step in said process; Fig. 6 is a perspective view of the tube shown in Fig. 5; Fig. 7 is a perspective view similar to Fig. 5 showing the tube after the application of 45 a sand-blast; and Fig. 8 is a fragmentary section of the tube, showing the roughnesses created by the sand-blast.

In the practice of my invention, a sheet 1, as shown in Figs. 1 and 2, is first bent at its 50 ends as at 2 for a reason to be later set forth.

A second operation forms the sheet into a horse-shoe shape as shown in Fig. 4, while a third operation brings the free ends 3 into juxtaposition and forces them closely together as at 4.

55

It should here be noted that by my invention I am enabled to form a tube from a sheet of metal in three simple operations, forming a tight joint between the ends of the sheet. The formation of this tight joint is dependent upon the bends 2 formed by the first operation. Without such bends, after the half-round dies had forced the ends 3 together and had been removed, the resiliency of the metal would tend to cause the ends 3 to spring apart. This separation might be very slight, but it would be fatal to the efficiency of the bearing.

55

If, however, the bends 2 are present when the dies close upon the tube, when it is shaped as shown in Fig. 4, the ends 3 follow the shape of the lower die until they come into contact with each other, at which time the dies are almost, but not quite, closed.

60

Further movement of the dies acts on the bends 2 with a toggle effect, thus forcing the ends 3 together with a pressure impossible to attain by the usual methods. When, after such action, the dies are released, the joint 4 is found to be entirely tight, since the natural 75 resiliency of the metal tends now to force the ends 3 closer together.

80

After the tube has been formed in the manner outlined above, it is treated with a sandblast to clean and roughen its entire surface 85 as indicated at 5 in Figs. 7 and 8. This roughening is effected by the minute indentations made by the grains of sand as they are thrown by compressed air with a high velocity against the surfaces of the tube. The 90 roughness imparted by this treatment is not very pronounced and is more or less uniform over the whole surface of the tube.

85

Of course, although I prefer to use a tube which has been formed from sheet metal, in 95 the practice of my invention, it will be readily understood that the sand-blast could be applied as well to roughening the surfaces of a tube which had been formed in any other way.

100

As has been stated above, I find my invention to be most advantageous in the manufacture of bearings, and more particularly in the manufacture of main bearings for the crank shafts of internal combustion engines. There exists a demand for bearings of this type which can be manufactured less expensively than those now on the market, and my invention meets that demand. In manufacturing bearings of this type, in accordance with my invention, the above outlined process is carried through and then the sandblast-roughened tube is dipped into a bath of molten tin, after which Babbitt metal is cast onto the inner surface of the member by the centrifugal method. Because of the roughness of the surfaces of the tubular member, the coating of tin adheres very closely to the tubular member and the general effect is almost as efficient as though the tin had been welded onto the whole surface of the tubular member. The Babbitt coating is then turned down to absolute smoothness and concentricity with the outer surface of the tubular member, and the tube is split to form the semi-cylindrical features of a completed bearing.

It will be seen that I have devised a method whereby an improved bearing may be manufactured at very slight cost and with a minimum expenditure of time.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

- 40 1. The method of making lined bearings which consists in forming a sheet into a cylinder having a pressure-tight butt joint, minutely roughening the inner surface thereof by a percussive action, tinning such surface, casting a layer of bearing metal on such roughened surface, and machining the outer and inner surfaces of the composite articles thus formed.
- 45 2. A cylindrically curved bearing blank having a surface provided with a multiplicity of minute irregularly arranged recesses produced by a percussive action.

Signed by me this 20th day of May, 1927.

55 WILLIAM H. KLOCKE.
